UNITED STATES PATENT OFFICE.

WILLIAM LINDSAY, OF CHICAGO, ILLINOIS, ASSIGNOR TO HENRY HYMAN & CO., INC.,
OF NEW YORK, N. Y., A CORPORATION OF NEW YORK.

ELECTRIC SWITCH MECHANISM.

Application filed January 3, 1922. Serial No. 526,751.

To all whom it may concern:

Be it known that I, WILLIAM LINDSAY, a citizen of the United States, residing in Chicago, in the county of Cook and State of Illinois, have invented certain new and useful Improvements in Electric Switch Mechanisms, of which the following is a specification.

This invention relates to that class of electric switch mechanisms in which a movable contact member is operated by actuating means comprising a rotative actuating member in movable relation to and adapted to operatively engage the movable contact member or contact bar to open and close an electric circuit.

The principal object of the invention is to provide a simple, economical and efficient electric switch mechanism.

A further object of the invention is to provide an efficient electric switch mechanism or pull switch comprising a movable contact member, and having a rotative reciprocating actuating means in movable relation to and adapted to operatively engage and press the movable contact member or contact bar into and out of circuit-making and circuit-breaking position so as to open and close the circuit with certainty and with a snap, and minimize the formation of an arc.

A further object of the invention is to provide an electric switch mechanism having a self-lubricating contact bar or movable contact member, and insulating means adapted to enable insulation of the ratchet from its support to be dispensed with.

Other and further objects of the invention will appear from the following description and claims, and from an inspection of the accompanying drawings, which are made a part hereof.

The invention consists in the features, combinations, details of construction, and arrangement of parts herein described and claimed.

In the accompanying drawings:—

Figure 1 is a view in side elevation of an improved electric switch mechanism constructed in accordance with my invention, and showing the same adapted for use with an electric lamp to be mounted in upright position on a suitable support or fixture, such, for instance, as a candelabra; Fig.

2 is a view in side elevation of the switch mechanism shown in Fig. 1, as the same would appear when viewed from the right of said Figure 1; Fig. 3 is a view in central vertical section taken on line 3—3 of Fig. 1, looking in the direction indicated by the arrows; Fig. 4 is a detail view in side elevation of the switch mechanism shown in Fig. 2, as the same would appear viewed from the right of said Fig. 2, and shows the stationary contacts, and the oscillating contact bar in engagement with said contacts, or in circuit-closing position; Fig. 5 is a view in side elevation of my improved switch mechanism, showing the same in connection with an electric lamp socket, which is shown partly in central vertical section, with the pull chain extending through a side opening in the shell of the lamp socket; said socket being adapted to be used on an ordinary fixture, with the lamp in horizontal position, or on any desired suitable support;

Fig. 6 is a view in transverse section taken approximately on line 6—6 of Fig. 1, looking downward, as indicated by the arrows, but showing the plunger actuating ratchet in section;

Fig. 7 is a view in transverse section, taken on line 7—7 of Fig. 1 looking in the direction indicated by the arrows, and showing the stationary contacts, and the movable contact bar in circuit-breaking position;

Fig. 8 is a view in transverse section taken on line 8—8 of Fig. 2, looking in the direction indicated by the arrows;

Fig. 9 is a view in central vertical section taken on line 9—9 of Fig. 3, looking in the direction indicated by the arrows;

Fig. 10 is a detail view in perspective of the frame, and shows the stationary sleeve on which the ratchet for operating the rotative reciprocating plunger is mounted, with the cam surfaces for engaging the lateral arms of the plunger;

Fig. 11 is an enlarged detail view in perspective, of the rotative reciprocating plunger for actuating the movable or oscillating contact bar;

Fig. 12 is an enlarged detail view in perspective of the oscillating ratchet, for operating the actuating plunger;

Fig. 13 is an enlarged detail view in

perspective, of the movable or oscillating centrally pivoted contact bar, showing the upper and lower metallic members thereof insulated from each other, and showing the 5 space for containing lubricating material;

Fig. 14 is an enlarged detail view of the upper metallic member of the oscillating contact bar shown in Fig. 13;

Fig. 15 is a detail view of the insulating 10 member or central fibrous body portion of the contact bar shown in Fig. 13; and

Fig. 16 is a detail view of the bottom metallic member of said contact bar.

In constructing an improved electric 15 switch mechanism in accordance with my invention, I provide a frame comprising a base 1 and an opposed or upper frame member 2 both formed of hard rubber, fiber or other suitable insulating material, and connected in rigid relation with a suitable space therebetween, by means of suitable connecting members 3 and 4 which are, by preference, formed of metal so as to form electric conductors which are connected with 20 the stationary contacts and embraced within the electric circuit to be opened and closed by my improved switch mechanism, as hereinafter more particularly described.

In the form of the device shown in the 25 drawings the stationary contact member or pin 5 is mounted in the frame member 2 of insulating material. This metallic contact member or pin 5 is connected with the central or positive spring contact 6 which is 30 in position to engage the central contact 7. The contact 7 in this instance is one of the terminals of the carbon filament of an ordinary incandescent lamp 8, and the contact 7 is surrounded by insulating material 9 in 35 the usual manner. The contact members 5 and 6 being mounted in insulating material forming the part 2 and in the transverse projecting rib 10, are thus normally out of 40 contact with all other electrically conductive parts except the contact 7 or a corresponding contact of any suitable type to be connected with the part 6 or contact 5 to form an electric circuit for lighting or for any desired purpose. The metallic outer shell 45 11 of the threaded neck of the incandescent lamp bulb 8 is connected with and forms the opposite terminal of the filament of the lamp, or of the conductor with which the contact 7 is connected; and the outer metallic member 12, which in this instance is 50 the threaded metallic shell of an ordinary incandescent lamp socket, is in contact with the conductor or outer shell 11,—which in this instance is the outer shell of an incandescent lamp neck—and electrically connected with the metallic standard or negative binding member or binding post 4 by 55 means of a metallic screw 13. The screw 13 extends through the flange 14 of the metallic member 12 or socket and through the insu-

lation 2, and through and in threaded engagement with the angular end flange 15 of said metallic standard or negative binding post 4. A metallic binding screw 16 in threaded engagement with the binding post 70 4 serves to bind an electric wire 17 in contact with the post or standard 4. The wire 17 is, of course, connected in any desired ordinary or suitable manner with one of the poles—for instance, the negative pole—of a 75 dynamo or source of electric supply. The post 4 with its binding screw 16 thus serves as a negative terminal and binding post, and also serves as a connecting means for holding the insulation 2 and base 1 of insulating 80 material in rigid relation and properly spaced apart.

A stationary contact 18, in the insulation 2 and transverse projecting rib 10 of insulating material,—in which the contact 5 and its spring contact 6 are mounted and normally insulated from all other electrically conductive parts except the contact 7 or lamp filament terminal—is connected at its upper end with the upper angular end or flange portion 19 of the metallic binding post or standard 3. And a binding screw 20 in threaded engagement with the positive binding post 3 serves to bind an electrically conductive insulated wire 21 with said positive binding post 3. The bottom extremity of the contact 18 thus extends through the insulating rib 10 and is in the same plane with the corresponding exposed end of the contact 5. The contacts 5 and 18 are thus, 90 of course, normally insulated from each other, and are strong and rigid. The electric wire 21, leading from the positive binding post 3 and binding screw 20, is adapted to be electrically connected with a corresponding pole of a dynamo or source of electric supply, for lighting or other purposes 95 as desired.

From the foregoing it will be readily understood that in order to form a closed 100 electric circuit it is only necessary to electrically connect the contacts 5 and 18 in a suitable manner, and that by disconnecting said contacts the circuit will be broken.

In order to enable this and other desirable purposes to be accomplished in an efficient manner in accordance with my invention a supporting bracket or frame 22 is mounted between the base 1 and the insulation 2. This frame comprises an upper or 115 angular supporting arm or head 23 secured to the insulating member 2 by means of screws or other ordinary suitable securing means, and a depending or upright plate 24, which is located centrally between the 120 base 1 and insulation 2 and at right angles to the parallel opposed faces of said base and plate-supporting insulating member 2. (See Figs. 2, 3, and 10.)

The plate 24 may be formed in one in- 130

tegral piece or fixed to and supported by the part 23 or by other suitable means. Mounted on this supporting plate 24 or other suitable supporting means which may 5 be of any desired or suitable form, is a fixed hollow sleeve or tube 25. This tube or sleeve 25 projects from one side of the plate 24, and has its longitudinal axis and its cylindrical walls in perpendicular relation to the side 10 face of the plate 24 and in parallel relation to the opposed walls or faces of the base 1 and opposed insulating plate-supporting member 2 already described. On the opposite side of the plate 24 from the stub shaft 15 or tube 25 is mounted a movable contact member or bar 26 which comprises in its construction a main upper hollow metallic main outer body member 27 which is substantially U-shaped in cross section, as 20 shown in Figs. 13, 14, 2 and 3, an opposite metallic contact bar member or supporting section 28, which is also U-shaped in cross section, and an inner insulating connecting member or core 29, formed of hard rubber 25 or fibrous insulating material and adapted to fit tightly within the hollow portions of both of said opposite metallic U-shaped members 27 and 28, and support both of 30 said metallic members in insulated spaced apart relation to each other, thus forming a rigid contact bar comprising opposed metallic members insulated from each other but rigidly connected with the intermediate insulating member or core. A 35 space 30¹ is provided between the insulating core 29 and the U-shaped metallic contact bar member 27 which is adapted to contain suitable lubricating material, for lubricating the contact bar.

40 The contact bar thus formed is provided with opposite trunnions 30, 31. The trunnion 30 which is fixed to the part 28 is pivotally mounted in a suitable bearing recess in an arm 32 which projects from a marginal portion of the plate 24 and may be formed in one integral piece with said arm. The trunnion 31 is pivotally mounted in a suitable bearing 33 in the depending rib 10 of the insulation member 2 already described. The 45 trunnions thus form an axis about which the contact bar 26 is adapted to oscillate, the axial center being by preference, at the longitudinal center of the contact bar and in perpendicular relation to the plane in 50 which the contacts 5 and 18 are located, and midway between said stationary contacts 5 and 18. It follows that said axis is parallel to the side faces of the plate 24 and perpendicular to the opposed inner 55 faces of the base 1 and the insulation member 2 above described. The outer or convex face of the main or upper metallic U-shaped plate or movable contact member proper 27, which forms the main metallic portion of 60 the contact bar 26, is perpendicular to the

axis of oscillation of said contact bar, and therefore, adapted to be swung into and out of contact with the fixed contacts 5 and 18.

The contact bar 26 is yieldingly supported 70 in such a manner as to yieldingly engage the contacts 5 and 18 when the bar is in circuit closing position, by means of a compressible spring 34 which encircles the trunnion 30, and is interposed between the bar-supporting foot or arm 32 and the lower metallic member 28 in which the trunnion 30 is anchored. The plate 28 has an elongated recess 35 in the face which is toward the plate 24; and the insulating material adjacent to the plate 28 is recessed sufficiently so that the plate affords a bearing face 36 which is adapted to engage the oblique foot of the rotative reciprocating actuating plunger hereinafter described, and permit 80 the plunger to rotate a half of a revolution while in detached relation to the contact bar each time the contact bar is to be actuated by the plunger and without moving or oscillating the contact member until the plunger 85 is moved longitudinally while in operative engagement with the contact bar, and more specifically, in contact with the surface 90 of the plate 28 which forms one of the outer metallic insulated members of the 95 contact bar.

Rotatively mounted in and movable longitudinally on the inside of the fixed hollow stub shaft or plunger-and-ratchet-supporting tube 25, is an actuating plunger 37, 100 one extremity of which extends through the plate 24 and is provided with an oblique angular foot 38, the longest arm or toe 39 of which extends outward laterally and endwise beyond the end of the central stem portion of the plunger, and endwise beyond the outer extremity of the opposite relatively short arm or heel 40 of the foot or shoe 38. The end face or margin 41 of the oblique foot 38 is, by preference, slightly 105 concave. The foot 38, and particularly the end marginal face 41 thereof is thus in oblique relation to the longitudinal center and axis of the rotative reciprocating contact-bar-actuating plunger 37, and said foot 110 38 and oblique margin or face 41 are adapted to engage the side of the contact bar 26 and cause said contact bar to be moved into circuit closing or circuit breaking position in oblique relation to the longitudinal axial center of the plunger, the oblique position of the contact bar corresponding in each instance with the position and oblique relation of the shoe 38 with respect 115 to the axis or longitudinal center of the 120 plunger.

The actuating plunger 37 is reciprocated or moved longitudinally in one direction and toward and into contact and operative engagement with the contact bar 26 by 130

means of a plunger-actuating spring 42 which is, by preference, in the form of a steel wire folded upon itself and forming a central loop 43 which encircles the neck 5 of the plunger 37 just back of the shoulder 45¹ formed by the foot 38. The opposite extremities of the spring 42 are each formed into a loop 45 each of which encircles a finger or spring-supporting projection 10 on the plate 24 already described. The end portion of each loop 45 extends between the body of the spring and said plate 24 and forms a support or fulcrum over which the spring is bent. The spring is thus held in 15 operative position in an efficient manner, and is readily mounted in place or removed. The spring 42 thus acts as a suitable resilient means for actuating the plunger 37 to move it longitudinally in one direction or 20 toward and into operative engagement and actual contact with the metallic plate member 28 of the contact bar 26, which metallic plate is insulated from the main metallic member 27 of the oscillating contact bar 25 which comes into actual electrically conductive contact with the contacts 5 and 18 above described, to close the electric circuit.

The plunger-actuating spring 42 also acts 30 to move the plunger longitudinally in the same direction to break the electric circuit, as well as to close it. But the plunger is rotated one half of a complete revolution or 180° from its circuit-closing position, in order to reach its circuit-breaking position.

35 And at the end of its movement to circuit-closing position, as well as at the end of its circuit breaking position, the oblique face or edge of the plunger or plunger foot 38 is in engagement with the side face of the plate 28 of the contact bar 26. The contact bar 26, in each instance, occupies a position oblique to the longitudinal center of the actuating plunger. And the oblique angle of the foot 38 which is inverted with 40 each operation of the plunger, or, in other words, with each half of a revolution of the plunger, determines the angular position of the oscillating contact bar 26 with respect to the axis or longitudinal center 45 of the plunger. It follows, as a matter of course, that when the plunger is in the position shown in Fig. 6, and the oscillating or pivoted contact bar 26 is in the corresponding position or at the corresponding 50 angle in which it is shown in Figs. 6 and 7, the circuit will be broken, as the contact bar 26, when in the position shown in said figures, is out of contact with the contacts 5 and 18. And it is plain that by 55 inverting the plunger 37 or turning it one half of a complete revolution from the position in which it is shown in Fig. 6, the contact bar 26 will be turned to a correspondingly different angular position or to circuit-closing position and in contact with the

contacts 5 and 18, as shown in broken lines in Fig. 7. The plunger 37 and contact bar 26 are also shown in circuit-closing position in Fig. 8, the actuating plunger 37 in Fig. 8 being in the circuit-closing position 70 which it would reach upon being inverted or turned one half of a revolution from the position in which it is shown in Fig. 6.

It should be noted that the rotative reciprocating actuating plunger 37 is detached 75 from and freely movable with respect to the oscillating or movable contact bar 26 which it actuates, and that it is adapted to move longitudinally in one direction in response to the action of the spring 42, and in 80 an opposite direction against the tension of said spring. And with each longitudinal movement of the actuating plunger 37 in a direction against the tension of the actuating spring 42, or, in other words, in a 85 direction away from the oscillating contact bar 26 to be actuated by the spring-pressed actuating plunger, the said plunger 37 makes one-half of a complete revolution; but it does not revolve during its movement 90 in the direction in which it is pressed longitudinally by the spring 42. The actual rotation of the actuating plunger during each of its longitudinal movements against the tension of the spring and away from the 95 contact bar 26 is therefore accomplished uniformly and with accuracy and certainty without disturbing or changing the position of the contact bar 26 during the rotative movements of the plunger, which, in fact, 100 may be entirely out of contact with the contact bar 26 during a part of the rotative movement or movements of the plunger, as such movements occur intermittently between the non-rotating longitudinal movements which are produced by the action of the plunger-actuating spring 42. And the spring actuates the plunger and the contact bar with a sudden quick movement and with a snap, both in opening and in closing 110 the circuit.

It is desirable to provide simple and efficient means for rotating the actuating plunger 37 during each longitudinal movement of the plunger against the tension of its actuating spring 42, or away from the oscillating contact bar 26, and means for positively operating said plunger longitudinally against the tension of said 115 spring simultaneously with or during each 120 intermittent partial or half revolution of the plunger.

In order to accomplish these and other desirable objects of my invention in a simple and efficient manner, I provide a pair of laterally projecting arms 47, 47 upon the outer end of and, by preference, formed in one integral piece with the body of the plunger 37. The hollow cylindrical stub shaft or tube 25 is provided with a serrated 125

end surface or annular edge at its outer end. These serrations or endwise-projecting teeth 49, of which there are two, each extending part way around the annular end of the tube, each form a curved inclined cam or cam face 48 which faces endwise or outward in position to engage the lateral arms 47 on the plunger. These end cams or cam surfaces are in inclined oblique relation to the plane in which the arms 47 are located, and said arms are in a plane which is perpendicular to the longitudinal center and axis of the rotative reciprocating plunger 37. And said end cams or cam surfaces 48 are helical. But they each extend only half way or substantially half way around the annular end margin or edge of the tube and outward at an incline or oblique angle to the longitudinal center or axis of the tube and in the direction of rotation of the plunger 37, as shown in Figs. 6, 7, 8, and 10. These oblique or helical cams or cam surfaces each terminate at the outer endwise extremity of each cam, serration or tooth 49, respectively. And the points of the teeth or serrations are located on diametrically opposite sides of the axis and longitudinal center of the tube 25 and of the rotative reciprocating plunger 37. The outermost endwise pointed extremity of each cam or serration 49 projects outward endwise of the tube beyond and in offset relation to the adjacent inner extremity of the next adjacent cam or serration, and forms a shoulder 50 which converges at its base with the base or inner extremity of such adjacent cam, so as to provide notches 51 of sufficient depth longitudinally of the tube to receive and permit the movement of the lateral arms 47 of the plunger 37 from the outermost pointed extremities of the teeth 49 to the bottoms of the triangular notches thus provided between the serrations, teeth or cams 49.

45 An oscillating toothed ratchet 52, which may be in the form of a circular disk or plate having ratchet teeth 53, 53, on the outer side of the plate and encircling the inner margin or perimeter 54 of the same, is mounted upon and in position to encircle the tube 25, and to oscillate or turn half-way around the tube, first in one direction and then in the opposite direction alternately, to rotate the plunger 37 intermittently or in a step by step manner, half a revolution at each step. The ratchet teeth 53 on the ratchet member 52 are of substantially the same shape and dimensions as the cams or serrations 49 on the end of the tube 25, as already described; but the ratchet teeth 53 encircle the axial opening 55 in the center of the ratchet 52, and extend around the outside of and in sliding freely oscillating engagement with the outer peripheries of the cam teeth or serrations 49 on the tube,

and form shoulders 56 the end margins of which are undercut, as shown in Fig. 12, and adapted to engage the adjacent protruding edges 57 of the lateral arms 47 on the rotative reciprocating plunger 37, and rotate the said plunger intermittently, or in a step by step manner, one-half of a revolution at each step.

46 A flexible element, which may be in the form of a cord or chain 58, adapted to pass through an opening 59¹, or 60¹, as the case may be, (see Figs. 2, 5, 6, 7, and 8) is connected at one end with the ratchet 52 which is provided with a bayonet notch 59 for receiving and detachably connecting the chain with the ratchet. And a stop 60, on the margin of the plate 24 is mounted in position to stop or limit and determine the extent of the partial rotation of the disk or ratchet 52, which is provided with a detent or finger 61 on the margin of the ratchet and in position to engage and be stopped by the stop 60, when the ratchet is returned to its initial position by the spring 62. The spring is provided for the purpose of returning the ratchet to place after it is oscillated or moved part of a revolution each time the plunger 37 is to be rotated half a revolution by means of the pull chain 58. (See Fig. 7, also Figs. 6 and 8.) One end of the coiled helical spring 62 is connected with the frame 24, said connected end being shown in Fig. 7; and the other end of the spring is connected with the ratchet 52, as shown in Fig. 6. The spring 62 encircles the tube 25 and forms a flexible tube-encircling member or sleeve on which the chain 58 rests and is adapted to move as the chain is wound partially around, or unwound in operating the ratchet and thereby the plunger 37 in one direction, and releasing the plunger, and permitting the return of the ratchet in the opposite direction by the action of the spring 62, and the longitudinal movement of the plunger 37 by the action of the spring 42. The numeral 63 indicates the end of the spring 62 which is fastened to the plate 24 as shown in Fig. 7; and the numeral 64 indicates the other end of the spring which is fastened to the ratchet. The spring 62 tends to lightly press the ratchet outward longitudinally of the tube 25 against the arms 47, 47 on the plunger, so as to permit the ratchet to move outward longitudinally of the tube 25 with the plunger 37 during such outward longitudinal movement of the plunger. But the pressure of the spring 62 is so light as to be readily overcome by the action of the spring 42. And the action of the spring 42 in moving the plunger longitudinally against the relatively light spring 62 is not detrimentally affected by the action of the spring 62.

47 From the foregoing, it will be readily un-

derstood by those skilled in the art that the ratchet is oscillated in the direction necessary to cause the arms 47 on the plunger 37 to move from the inner to the outer extremities of the cam teeth 49, by pulling on the chain 58; that as soon as the arms 47 reach and pass over and beyond the outer pointed ends of the serrations or cams 49 on the end of the stationary tube 25, the spring 42 acts to suddenly move or snap the suddenly released plunger longitudinally in the direction of the oscillating contact bar 26, to be actuated thereby. And the spring 62 acts to return the oscillating ratchet 52 to initial operative position, with the ratchet teeth 53 in operative engagement with the radial arms 47 of the rotative reciprocating plunger 37, and in position to cause the arms 47, and thereby the plunger 37 to be rotated half 20 of a complete revolution and thereby inverted, each time the ratchet is operated.

I claim:

1. In an electric switch, the combination of a contact, a movable contact member adapted to be moved into and out of engagement with said first-mentioned contact, an actuating member adapted to operatively engage and actuate said movable contact member, resilient means for actuating said actuating member in one direction of its movement, cam mechanism in engagement with said actuating member, and actuating means encircling and in engagement with a projecting portion of said actuating member and adapted to intermittently rotate the same with respect to the engaged cam mechanism.

2. In an electric switch, the combination of a contact, a movable contact member adapted to be moved into and out of engagement with said first-mentioned contact, an actuating member adapted to operatively engage said movable contact member, means for actuating said actuating member in one direction of its movement, and cam and ratchet mechanism encircling in operative engagement with said actuating member, and acting to intermittently rotate and actuate the same in an opposite direction of its movement.

3. In an electric switch, the combination of a contact, a movable contact member adapted to be moved into and out of operative engagement with said first-mentioned contact, an actuating member adapted to operatively engage said movable contact member, resilient means for actuating said actuating member in one direction of its movement, stationary cam mechanism in operative engagement with said actuating member, and ratchet mechanism movable independently longitudinally of the axis of said rotative actuating member and adapted to intermittently rotate the same with respect to the engaged cam mechanism.

4. In an electric switch, the combination of a contact member, a movable contact member adapted to be moved into and out of operative engagement with said first-mentioned contact, an actuating plunger adapted to operatively engage said movable contact member, resilient means for actuating said plunger in one direction of its movement, a stationary cam member in engagement with said plunger, plunger-actuating means encircling said cam and in operative engagement with said actuating plunger, for rotating the same with respect to the engaged cam mechanism, and means for operating said plunger-actuating means.

5. In an electric switch, the combination of a stationary contact member, a movable contact member adapted to be moved into and out of operative engagement with said stationary contact, an actuating plunger adapted to operatively engage said movable contact member, resilient means for actuating said plunger in one direction of its movement, a tubular member through which said plunger extends, said tubular member having cam faces at one extremity thereof adapted to operatively engage the plunger, a ratchet mounted on and encircling said tubular member and in operative engagement with said plunger, means for operating said ratchet in one direction, to cause the plunger to move in a corresponding direction in opposition to the action of the plunger-actuating resilient means, and means for operating the ratchet in an opposite direction to initial position.

6. In an electric switch, the combination of a contact member, a movable contact member adapted to be moved into and out of operative engagement with said first-mentioned contact, an actuating plunger adapted to operatively engage and actuate said movable contact member, resilient means for actuating said plunger in one direction of its movement, a stationary cam encircling said plunger, an arm on said plunger and in engagement with said cam, a reciprocating ratchet in operative engagement with said plunger arm, for rotating the plunger with respect to the cam, and means for operating said ratchet.

7. In an electric switch, the combination of a contact member, a reciprocatory contact member movable into and out of operative engagement with said first-mentioned contact, a plunger having an angular marginal end portion in oblique relation to the longitudinal axis of said plunger and in detached relation to and adapted to actuate and positively stop said reciprocatory contact member with respect to the axis of said plunger and the first-mentioned contact member, means for actuating said plunger in one direction of its movement, to operate said reciprocatory contact member, and means for

intermittently rotating and actuating said plunger in an opposite direction with respect to said reciprocatory contact member.

8. In an electric switch, the combination of a contact member, an oscillatory contact bar movable into and out of operative engagement with said first mentioned contact, a plunger having an angular marginal end portion in oblique relation to the longitudinal axis of said plunger and in detached relation to and forming a movable stop for positively stopping said oscillatory contact member with respect to the first-mentioned contact, means for actuating said plunger in one direction of its movement, and means for rotating said plunger and actuating the same in an opposite direction with respect to said oscillatory contact member.

9. In an electric switch, the combination of a contact, a reciprocatory contact bar movable into and out of engagement with said first-mentioned contact, an actuating plunger having an angular marginal end foot provided with an end surface in oblique relation to the longitudinal axis of said plunger and in detached relation to and adapted to operatively engage said reciprocatory contact bar, radial arms on the opposite extremity of said plunger from said angular foot, a cam having a cam surface in engagement with said radial arms and acting to move said plunger in a direction away from said reciprocatory contact bar when the plunger is intermittently rotated, means for intermittently rotating the plunger, and means for actuating the plunger in the direction of and in operative engagement with the reciprocatory contact bar.

10. In an electric switch, the combination of a pair of stationary contacts, a pivoted contact bar having separate trunnions forming an axis which is disposed at an angle to the plane in which said stationary contacts are located, insulating means on said bar and adapted to hold said trunnions in operative position with respect to each other and in insulated relation, and means for moving said insulated pivoted contact bar into and out of position to form an electrical connection between said stationary contacts.

11. In an electrical switch, the combination of a pair of stationary contacts rigidly supported and normally insulated from each other, a pivoted contact bar comprising in its construction a pair of metallic members each provided with a trunnion, said trunnions forming an axis which is disposed at an angle to the plane in which said fixed contacts are located, an insulating body forming part of said bar and forming a rigid connection between and acting to hold said metallic bar members in rigid spaced-apart insulated relation to each other and in position to enable one of said insulated metallic

contact bar members to be moved into and out of position to form an electrical connection between the fixed contacts, and means for moving said pivoted contact bar into and out of position to form an electrical connection between said fixed contacts.

12. In an electric switch, the combination of a pair of fixed contacts normally insulated from each other, a pivoted contact bar comprising in its construction a pair of separated metallic contact-bar members each provided with a trunnion, said trunnions forming an axis in perpendicular relation to the plane in which said fixed contacts are located, an insulating body forming part of said bar and forming a rigid connection between and acting to hold said separate metallic bar members in rigid insulated relation to each other and in position to enable one of said metallic members of said contact bar to be moved into and out of position to form an electrical connection between the fixed contacts, and means for moving said pivoted contact bar into and out of position to electrically connect said fixed contacts.

13. In an electrical switch, the combination of a pair of fixed contacts normally insulated from each other, a pivoted contact bar comprising in its construction a pair of separate metallic members each provided with a trunnion, said trunnions forming an axis which is disposed at an angle to the plane in which the fixed contacts are located, a core of insulating material forming part of said bar and forming a rigid connection between and acting to hold said separate metallic bar members in rigid insulated relation to each other and in position to enable said bar to be moved into and out of circuit-closing position with respect to said fixed contacts, means for moving said insulated electrically conductive contact bar into and out of position to connect said fixed contacts, and resilient means in engagement with and adapted to yieldingly hold said contact bar in circuit-closing position.

14. In an electrical switch, the combination of a pair of fixed contacts normally insulated from each other, a pivoted contact bar comprising a pair of separate metallic members each provided with a trunnion, said trunnions forming an axis adapted to permit the pivotal movement of the bar into and out of position to form an electric connection between said fixed contacts, a core of insulating material forming a part of said bar, and forming a rigid connection between and acting to hold said separate metallic bar members in rigid insulating relation and in position to enable one of said metallic bar members to form an electrical connection between said fixed contacts when said bar is in circuit-closing position, and actuating means adapted to engage the other one of said metallic bar members only,

- to move said bar into and out of position to connect said contacts.
15. In an electric switch, the combination of a contact, a movable contact member comprising in its construction an insulating body, and a metallic part fixed to said insulating body and adapted to be moved into and out of contact with said first-mentioned contact and embraced within the same electric circuit with the same, said movable contact member having a recess therein for containing a lubricant for lubricating said metallic part of said contact member, and means for operating the movable contact member,
16. In an electric switch, the combination of a contact, a pivoted contact bar having trunnions forming a support therefor, said contact bar comprising in its construction an insulating body, and a metallic part fixed to said insulating body and adapted to be moved into and out of contact with said first-mentioned contact, a second metallic part fixed to said insulating body and forming a support for the same, and actuating means adapted to engage said last-mentioned metallic part, for moving said pivoted contact bar into and out of electrical connection

with the first-mentioned contact, to open and close the electric circuit.

17. In an electric switch, the combination of a contact, a movable contact member, and actuating means in operative engagement with said movable contact member, for moving the same into and out of circuit-closing position with respect to the first-mentioned contact, said actuating means comprising a ratchet, an axle on which said ratchet is mounted, means for operatively connecting said ratchet with said movable contact member, a helical spring encircling said axle and having one end connected with said ratchet, the opposite end of said spring being connected with a suitable support, and a flexible element connected with said ratchet and extending partly around and resting upon said spring, for operating the ratchet in an opposite direction to that in which the tension of the spring tends to move the same.

Signed at Chicago, in the county of Cook and State of Illinois, this 30th day of December, 1921.

WILLIAM LINDSAY.
